UNITED STATES PATENT OFFICE.

WILLIAM G. WOOD, OF SAN FRANCISCO, CALIFORNIA, ASSIGNOR TO BERKELEY LIGHT CORPORATION, OF SAN FRANCISCO, CALIFORNIA, A CORPORATION OF NEVADA.

HEADLIGHT.

1,400,926.

Specification of Letters Patent. Patented Dec. 20, 1921.

Application filed August 5, 1918, Serial No. 248,803. Renewed March 3, 1920. Serial No. 383,084.

To all whom it may concern:

Be it known that I, WILLIAM G. WOOD, a citizen of the United States, residing at San Francisco, in the county of San Francisco and State of California, have invented new and useful Improvements in Headlights, of which the following is a specification.

This invention relates to improvements in light projectors, and more particularly to headlights, such as are adapted for use on automobiles, locomotives, street cars and the like.

This application is a continuation in part of my prior application Serial No. 209,834 filed January 2, 1918, which has become Patent No. 1,324,288 dated December 9, 1919.

Lamps of the headlight type, such as are commonly employed on automobiles and the like, are ordinarily provided with a parabolic or like reflector to concentrate the rays and to permit the projection of a single beam of intense light.

In actual practice it is found impossible to regulate the vertical height of the beam projected as imperfections in the parabolic reflector and the size of the filament produce a cone-shaped beam and not a series of parallel rays, as theoretically intended. While the source of light itself may not be of great intensity the projection and concentration of its rays produces a light beam so intense as to be in effect blinding to the eyes of approaching drivers or pedestrians, particularly if the field of the projected beam is entered. Many attempts have been made to prevent the glaring or blinding effect thus produced and to regulate the vertical height of the rays projected. For instance, dimmers, shutters, refractory lenses and other devices have been employed, but the general result is a mere reduction of the lighting power of the lamp.

One of the objects of the present invention is to overcome this defect and to provide a headlight which permits concentration and projection of the light rays on the roadway ahead of the automobile, and which also permits spreading of the beam laterally while confining it vertically, that is, the projector or reflector from which the light emanates may be so arranged that no light rays are permitted to project above a horizontal line drawn on a level with the lamp.

Another object of the invention is to provide a reflector which projects a concentrated

light-beam in which the rays cross each other at a common focal line and then spread; and also to provide a lamp having a small slit-like window or transparent aperture through which the rays are projected, this window being preferably placed at the focal point or crossing line of the rays, thus permitting a reduction in the size of the exposed area of the window to half an inch or less in width.

Another object of the invention is to provide a novel shutter arrangement adapted to be interposed between the transparent aperture and the projecting reflector, said shutters permitting an unobstructed projection of substantially all the light rays from the interior of the lamp outwardly and at the same time serving the function of shutters when the lamp is viewed from the exterior, as they completely hide the source of light and the apparent source, the blades overlapping on the line of vision unless the eye is below the lamp and in the projected field of light.

Another object of the invention is to provide means for converging or diverging the light beam as it passes through the transparent aperture to increase or decrease the area lighted, and to produce a more uniform field of light.

Further objects will hereinafter appear.

The invention consists of the parts and the construction, combination and arrangement of parts as will be hereinafter more fully described and claimed, having reference to the accompanying drawings, in which—

Figure 1 is a central, vertical, longitudinal section through the lamp.

Fig. 2 is a diagrammatic view showing how the light beam may be converged or diverged by placing a lens in the transparent aperture.

Fig. 3 is a plan view partly in section.

Fig. 4 is a front view of the lamp.

Figs. 5 and 6 are diagrammatic plan and side elevations of the projecting reflector, respectively.

Referring to the drawings in detail, and particularly to Figs. 1 and 3, A represents a casing in the forward end of which is placed an oblong narrow window or transparent aperture 2. The casing proper is shaped as shown, and is comparatively narrow when viewed from the top, as shown in Figs. 1 and 3, and consists of two sections 3 and 4

which are secured together in any suitable manner, but preferably by an eccentric snap fastener, as here shown, to permit the upper section 4 to be quickly and readily removed when desired.

Suitably secured to the interior of the casting is a reflector cage, generally indicated at B. This cage is substantially circular in shape and is provided with two outwardly projecting lugs 5 which pass through the sides of the casing section 3, said lugs being provided with socket openings 6 to permit the lamp as a whole to be supported upon uprights or forks of the usual construction. The reflector cage is also provided with a recess in the bottom portion for the reception of a parabolic reflector 7, and it is furthermore provided with two upwardly extending arms 8 provided with bearing caps 9 at their upper ends for the reception of a cross rod 10 which supports a projecting reflector, generally indicated at 11.

This reflector is approximately rectangular in shape when viewed either from the front or the rear, and is provided with projecting lugs 12 to permit it to be secured to the cross rod 10. The forward face of the reflector is curved, as shown, the curvature at the upper end of the reflector being struck from a shorter radial point than the curvature at the lower portion of the reflector. It is in reality nothing more or less than the segment of a cone, as shown in Figs. 5 and 6, and it therefore permits the forward projection of a horizontal beam, the height of which is proportional to the size of the reflector and the diameter of the beam projected thereon, while its width may be varied in proportion to the curvature of the reflector or the size of the cone from which the reflector is taken.

The axis of the cone of which the reflector 11 is a section is represented by the dotted lines $x-x$ in Fig. 6. This line coincides with the vertical aperture 2 and is parallel with the incident rays. Practically all the rays projected by the reflector 11 will cross or focus on this line, as indicated in plan in Fig. 5.

The lower parabolic reflector 7 is provided with an electric light 14, the filament of which is located at the approximate focal point of this reflector, said light being preferably adjustable along the vertical axis of said reflector to prevent any portion of the filament from projecting beyond the focal point. Practically all the rays reflected by the parabolic reflector will therefore be parallel and when received by the reflector 11 will be projected forwardly in the form of a wedge-shaped beam, such as shown by the dotted lines 15 in Fig. 3, the focal point or crossing line of said rays being located in the transparent aperture 2, therefore permitting spreading of the beam or the rays

after leaving the aperture. Theoretically, it will only be necessary to provide a slit-like opening in the front of the lamp not much wider than a thirty-second of an inch. I, however, provide an opening half an inch in width as any movement of the projecting reflector 11 will thus be taken care of. The spreading of the beam, as previously stated, can be increased or decreased as much as desired by changing the curvature of the reflector 11, and also by the insertion of a lens in the transparent aperture as will herein-after be described.

For the purpose of raising or lowering the projected beam I provide a manual control. A projecting arm 17 secured either to the reflector or the cross rod 10 is, in this instance, connected with a flexible cable or wire 18 which passes through a tube 19 and out of the casing. This wire may be attached to a push rod or operating lever conveniently located within reach of the driver either on the steering column or on the dashboard. This rod or lever when moved by the driver will swing the reflector 11 secured to the cross rod 10 in the bearings 9, thus changing the angular position of the reflector 11 with relation to the stationary parabolic reflector 7. This raises or lowers the projected beam and thus permits the beam to be projected ahead of the vehicle at all times, notwithstanding changes of grade as when approaching the foot of a hill, when as is well known, the range of illumination with ordinary headlights is very limited.

For the purpose of preventing the source of light or the apparent source of light from being visible through the slit-like aperture when the lamp is viewed from the exterior, a series of adjustable shutters 20 have been employed. These shutters are all pivotally mounted, as at 21, in a rectangular plate 22 secured within the casing intermediate of the reflector 11 and the transparent opening 2. The forward ends of the shutters are free to swing with relation to the aperture 2 while the rear ends of the vanes are all connected to an operating bar 23 which in turn is raised or lowered vertically by means of a bell crank 24 pivotally secured to one of the arms 8. The outer end of the bell crank 24 is slotted, as at 25, to engage a pin carried by the member 23, while the opposite arm of the bell crank is provided with gear teeth 26, as shown, which intermesh with the gear segment 27 secured either on the reflector or the cross rod to which it is secured.

Movement of the reflector 11 when it is being adjusted is thus transmitted through the bell crank to swing the shutters 20 in unison, either upwardly or in a downward direction, thus maintaining the same in parallelism with the light rays reflected by the projector and regardless of its angular po-

sition within the lamp casing. Comparatively few light rays are obstructed by the shutters 20, first, because they always assume a parallel position with relation to the projected rays, and, secondly, because they are so thin as to offer a comparatively small surface against the rays. The interposition of the shutters 20 between the transparent opening and the projector 11 positively prevents the forward projection of anything but parallel rays and they also serve as a means for concealing not only the source of light, but also the apparent source of light when the lamp is viewed from the exterior.

15 This can be readily understood when it is realized that the average person stands much higher than the lamps and will therefore look down upon same, for instance, on an angle assumed by the arrow *a*. The lamp when viewed from this angle apparently has no source of light, as all that can be seen will be the upper surfaces of the shutters 20. They form an obstruction to the line of vision, both as far as the source of light 20 is concerned and also the projector 11 when viewed from the angle indicated. It is therefore necessary for an observer to stoop down into alignment with the shutters before the apparent source of light becomes 25 visible. The projector or reflector 11 is adjustable with relation to the cross rod 10 by means of an arm 30 and a set screw 31. It may also be quickly removed with relation to the bearings 10 as the caps of the bearings 30 are hinged, as at 12^a, and secured when the reflector is inserted by spring latches 12^b.

If it is desired to remove the projector 11 it is only necessary to lift the heads of the latches 12^b to swing the same out of alignment with the caps as they are supported by 40 pivotally mounted links 12^c. The caps can thus be raised and the cross shaft 10, together with the projector carried thereby, may instantly be removed for cleaning, adjustment 45 or other purposes. The arm 17, by which the angular position of the projector is controlled, is segment-shaped or rounded on its lower end and engaged by a friction shoe 17^a to frictionally hold it in any adjusted 50 position. The rounded portion is also notched as at 17^b to normally secure the projector in the intended position, and also to permit the operator to feel or determine when the intended position is reached.

55 The forward portion of the lamp casing is preferably wedge-shaped, as shown in Fig. 3, to conform with the shape of the projected beam and it is therefore essential that the shutters 20 be of a similar shape. This 60 feature is, however, more or less unimportant, but shows that it is possible to considerably reduce the size of the lamp, if desired. The weight of the bell crank arm 24 and the connecting rod 23, by which the 65 shutters are moved, may be offset as in the

present instance by employing a counterbalance spring 40. A single shutter 41 may be placed within the reflector and cage to prevent forward projection of direct rays of light, if it is desired to eliminate the use of 70 the shutters 20.

By referring to Figs. 1 and 3 it will be seen that a plano convex cylinder lens has been placed in the transparent aperture. This lens has two functions, first, that of 75 converging or diverging the light beam projected, and second, that of producing a more uniform light field.

80 By referring to the diagrammatic view shown in Fig. 2 it will be seen that positioning of the lens behind the focal center 50 of the beam diverges the beam as indicated by the lines 51, while placing the lens ahead of the focal center converges the beam as shown by lines 52.

85 Practical experience has proven that these results are obtained, and also that a more uniform field of light is produced whether the lens is placed in one position or another, or at any intermediate point.

90 While a plano convex lens of the cylinder type is here illustrated, I wish it understood that any other lens or combination of the same, that is, a compound lens or the like, may be employed.

95 The materials and finish of the several parts of the lamp may otherwise be such as the experience and judgment of the manufacturer may dictate.

100 I wish it understood that various changes in the form, proportions and minor details of construction may be resorted to within the scope of the appended claims, and that I do not wish to limit myself to the specific design and construction here shown.

105 Having thus described my invention, what I claim and desire to secure by Letters Patent is:

1. A headlight comprising a casing, a source of light in said casing, means coöperating therewith adapted to project a beam of substantially parallel rays, a concentrating reflector adapted to receive said rays and project the same through a transparent aperture in the casing, said reflector having means which will project a beam of light having a vertical focal or crossing line for the projected rays. 110

115 2. A headlight comprising a casing, a reflector in said casing, said reflector comprising a section of a cone adapted to project a beam of light having a vertical focal or crossing line for the rays, a transparent aperture in the casing through which said rays are adapted to be projected, and means 120 within the casing for projecting a beam of substantially parallel rays against the sectional conical reflector.

125 3. A headlight comprising a casing, a reflector having means to project a beam of 130

- 4
- light having a vertical focal or crossing line for the rays, a transparent aperture in the casing positioned at the approximate crossing line of the rays, and means within 5 the casing for projecting a beam of substantially parallel rays against the said reflector, said means comprising a source of light and a parabolic reflector surrounding said light.
4. A headlight comprising a casing, a reflector in said casing, said reflector comprising a section of a cone adapted to project a beam of light having a vertical focal or crossing line for the rays, a transparent slit-like aperture in the casing positioned at the 10 approximate crossing line of the rays and means within the casing for projecting a beam of substantially parallel rays against the projecting reflector.
5. A headlight comprising a casing, a reflector in said casing, said reflector comprising a section of a cone adapted to project a beam of light having a vertical focal or crossing line for the rays, a transparent slit-like aperture in the casing positioned at the 15 axis of the cone, said transparent aperture being slightly larger than the area presented at a point drawn through the crossing line of the rays, a light in the casing and a parabolic reflector surrounding said light adapted to project a beam of substantially parallel rays against the said reflector, said rays being parallel to the axis of the cone.
6. In a lamp, a housing having a narrow vertical light emitting aperture, a source of light in the housing, means to reflect the rays from said source of light, and projecting means to receive the reflected rays, said last mentioned means being constructed and arranged to project substantially all reflected 20 rays in the form of a wedge shaped beam whose rays cross on a vertical line within the light emitting aperture and continue out therefrom divergently.
7. In a lamp or projector, a housing having a restricted emitting aperture, a source of light within the housing arranged to one side of the light emitting aperture and concealed from view therethrough, means to collect the rays emanating from the source of light and project them in the form of parallel rays directed at an angle to the transverse axis of the light emitting aperture, and separate means within the housing positioned to receive the parallel rays and 25 constructed and arranged to project them out through the aperture in the form of a beam whose rays tend in general to converge until reaching the aperture, and thereafter diverge, whereby to illuminate a field of appreciable area.
8. A headlight comprising a casing, a source of light in said casing, a reflector having means to project a beam of light having a vertical focal or crossing line for 30 the rays and a transparent aperture in the casing positioned at the approximate crossing line of the rays, said aperture being just sufficiently large in area to permit the crossing rays to be projected therethrough.
9. A lamp comprising a casing, a source of light in said casing, means co-operating therewith to project a beam of substantially parallel rays, and means to receive the parallel rays and project them out through the casing in the form of a beam having its rays 35 crossing on a line disposed substantially vertical.
10. A lamp comprising a casing having a narrow vertical aperture, a source of light in the casing, means to project rays of light from the source and a reflector to receive the projected rays and project them out through the narrow vertical aperture in the casing, said reflector having a surface generated by revolving a line, the axis of revolution of 40 which is coincident with the axis of the vertical aperture.
11. In a lamp, a source of light, means to project parallel rays therefrom, a reflector constructed to receive the parallel rays and project them in the form of a beam whose rays have a crossing or focal line parallel with the incident rays, said reflector being in the form of a section of the surface of a cone.
12. A lamp comprising a housing, a source of light in the housing, means co-operating with the source of light to project a large portion of the rays therefrom in a beam of parallel rays, and means to receive the beam 45 and project it out from the housing in the form of a convergent beam whose general direction is angularly disposed with respect to the axis of the incident beam, said second means being of a character to project a beam whose rays will meet and cross, and said housing having a light emitting aperture located where the rays of the convergent beam meet and cross, and restricted in size so as to effectually obscure the contents of 50 the housing.
13. In a lamp a housing having a restricted light emitting aperture in its front portion, a source of light in the bottom of the housing, a reflector surrounding the source of light, a second reflector near the top and rear of the housing to receive the rays from the first reflector, said second reflector being shaped and positioned to project a converging beam whose rays will meet and cross 55 within the restricted aperture and continue out divergently.
14. In a headlight, a housing having a slit-like aperture in its front portion for the emission of light, a source of light in the housing, means within the housing co-operating with the source of light to project a beam of parallel rays, and means to receive the parallel rays and project them in the form of a beam whose rays meet and cross 60

within the slitlike aperture and continue out in the form of a wedge-shaped beam.

15. A headlight comprising a casing, a reflector cage secured within said casing, a parabolic reflector secured in the lower end of said cage, a source of light in said parabolic reflector, a projecting reflector pivotally mounted in the cage above the parabolic reflector, a transparent opening in the casing, manually operated means for swinging the projecting reflector in its pivotal mounting, and means carried by the projecting reflector for normally maintaining it in a predetermined position.
- 15 16. A headlight comprising a casing, a reflector cage secured within said casing, a parabolic reflector secured in the lower end of said cage, a source of light in said parabolic reflector, a projecting reflector pivotally mounted in the cage above the parabolic

reflector, a transparent opening in the casing, manually operated means for swinging the projecting reflector in its pivotal mounting, and means carried by the projecting reflector for normally maintaining it in a predetermined position, said means comprising an arm movable in unison with the reflector, a friction shoe engageable with said arm and a notch formed in the arm with which the shoe is adapted to engage to normally retain the reflector in a predetermined position.

In testimony whereof I have hereunto set my hand in the presence of two subscribing witnesses.

WILLIAM G. WOOD.
